(57) **CLAIM**

The ornamental design for diagnostic connector adapter, as shown and described.

DESCRIPTION

FIG. 1 is a perspective view of a diagnostic connector adapter showing our new design;

FIG. 2 is a frontal view thereof;

FIG. 3 is a rear view thereof;

FIG. 4 is a side view thereof as viewed from the left-hand side;

FIG. 5 is a side view thereof as viewed from the right-hand side;

FIG. 6 is a top view thereof; and,

FIG. 7 is a bottom view thereof.

The broken line within the inner-most circle in FIGS. 1 and 2; and the broken line within the rear surface in FIG. 3 represents unclaimed portions of the diagnostic connector adapter and forms no part of the claimed design.
